DESIGN FOR A JEWELRY FINDING

Celia Robbins, New York, N. Y.

Application December 24, 1948, Serial No. 150,352

Term of patent 7 years

(Cl. D45—1)

To all whom it may concern:

Be it known that I, Celia Robbins, a citizen of the United States of America, residing at New York city, county of New York, State of New York, have invented a new, original, and ornamental Design for a Jewelry Finding, of which the following is a specification, reference being had to the accompanying drawing, forming a part thereof:

I claim:

The ornamental design for a jewelry finding, substantially as shown.

CELIA ROBBINS.
